(57) **CLAIM**

The ornamental design for a display for vehicle interior, as shown and described.

DESCRIPTION

FIG. 1 is a front, right side, perspective view of a display for vehicle interior showing our new design;

FIG. 2 is a front view thereof;

FIG. 3 is a rear view thereof;

FIG. 4 is a left side view thereof;

FIG. 5 is a right side view thereof;

FIG. 6 is a top view thereof;

FIG. 7 is a bottom view thereof;

FIG. 8 is a front, right side, perspective view of the display for vehicle interior in a configuration of use;

FIG. 9 is a front view thereof;

FIG. 10 is a rear view thereof;

FIG. 11 is a left side view thereof;

FIG. 12 is a right side view thereof;

FIG. 13 is a top view thereof; and,

FIG. 14 is a bottom view thereof.

The broken lines indicate portions of the article that form no part of the claimed design.

1 Claim, 8 Drawing Sheets
